UNITED STATES PATENT OFFICE.

HUGO R. KUERSTEN, OF CHICAGO, ILLINOIS.

CABINET-DOOR.

962,228.

Specification of Letters Patent. Patented June 21, 1910.

Application filed November 30, 1909. Serial No. 530,558.

To all whom it may concern:

Be it known that I, HUGO R. KUERSTEN, a citizen of the United States, residing at Chicago, in the county of Cook and State of Illinois, have invented certain new and useful Improvements in Cabinet-Doors, of which the following is a specification.

This invention relates to that type of cabinet door which is adapted to form a closure for the cabinet when swung into one position, and which, when released from such position, will swing into a position parallel with the side walls of the cabinet body, and when the latter position is reached will be acted upon by suitable mechanism and drawn back into the interior of the cabinet body.

The object of the present invention is to construct a door with the above described properties, in which the operation will be automatic which draws it back into position within the interior of the cabinet; in which the movement will be automatic which swings it into position to be acted upon by the mechanism to draw it back into the interior of the cabinet; which will be securely locked when it is in the position to form a closure for the cabinet; in which the door will be held against swinging movement while it is being drawn into or out of the cabinet body; in which the door cannot be swung into position to form a closure for the cabinet body until it has been fully withdrawn from the interior of the cabinet body; in which the upper and lower edges of the door will be forced to travel at a uniform rate of speed during the movement of the door into or out of the cabinet body; and which is capable of being attached to the ordinary cabinet body without any change in the appearance or construction thereof.

The invention consists in the features of construction and combination of parts hereinafter described and claimed.

In the drawings, Figure 1 is a vertical section showing the door in position to be drawn back into the interior of the cabinet body; Fig. 2, a sectional plan view of the parts shown in Fig. 1; Fig. 3, an enlarged side elevation of the pinion and rollers carried by the door, and the rack and trackway upon which the pinion and rollers travel, respectively; Fig. 4, a cross section showing the manner of mounting the pinion and rollers upon the door, and the manner of mounting the rack and trackway upon the cabinet

body; Fig. 5, a plan view of the parts shown in Fig. 3, and also the hinged connection on the door, and the stop member which prevents the door from swinging while it is being moved in and out of the interior of the cabinet body; Fig. 6, a detail of the locking mechanism for securing the door when it is swung into position to form a closure for the cabinet; Fig. 7, a section on line 7—7 of Fig. 6, showing the actuating mechanism in elevation; Fig. 8, a modified construction of the rack and pinion shown in Fig. 3; and Fig. 9, a cross section through the plate shown in Fig. 8.

The cabinet body consists of side walls 9, a rear wall 10, a top wall 11, and a bottom wall 12, all constructed in the manner ordinarily employed in manufacturing cabinet bodies. Positioned adjacent to the top wall 11 and the bottom wall 12, and secured to one of the side walls 9, are plates 13 and 14, preferably of angle-iron formation. Each of the plates has formed along the edge of one of its extending portions 15 gear teeth 16, and this toothed edge constitutes, in effect, a rack; and meshing with the teeth of these racks are pinions 17 and 18 which are mounted on a rod 19, which has its ends journaled within plates 20 and 21. These plates are also preferably of angle-iron formation and are secured to a section 22 of a cabinet door 23, which section is capable of a movement parallel only with the side walls of the cabinet body and may be termed the sliding section. The plates 13 and 14, as shown, are of angle-iron formation and have one of their extending portions formed as above described to constitute racks, the other projecting portion 24 forming a trackway upon which travel companion rollers 25 and 26 carried by the plates 20 and 21.

Attached to the section 22 of the cabinet door is a cable 27, which passes over an idler 28 journaled in the side wall 9 and positioned adjacent to the rear wall 10 of the cabinet body, which cable has a weight 29 secured to its end.

The cabinet door is composed of the section 22, which has been termed the sliding section, and a section 30, which is capable of movement parallel with the sides of the cabinet body, and is also capable of a swinging movement which will bring it into position to form a closure for the cabinet body, and this section may be termed the swinging section. The two sections are hinged to

gether by spring hinges 31 of any ordinary and well known type of construction. Located near the path of travel of the section 30 is a stop member 32 which is secured to the cabinet body and which prevents the door for swinging while it is being moved in or out therefrom. By referring to Fig. 5, where this stop member is shown more in detail, it will be seen that with the parts 10 as shown in this figure, the section 30 of the cabinet door is in position to be swung at right angles to the section 22 and form a closure for the cabinet; but if the parts were in a position so that the hinges 31 would lie on the opposite side of the stop member 32, it would then be seen that the stop member would act to prevent any swinging movement of the section 30; thus 15 no swinging movement of the section 30 is possible until the section has been fully drawn out from the interior of the cabinet, and no movement tending to draw the door into the interior of the cabinet is possible until the section 30 has swung into the 20 position parallel with the sides of the cabinet body, because not before it has reached such position will it be able to pass by the stop member. When the section 30 is swung into position to form a closure for the cabinet body, it is desirable that some locking 25 means be employed for retaining the section in such position. The locking means shown in Figs. 6 and 7, for accomplishing this purpose, consists of an actuating member 33 held normally outward under spring tension, and attached to the actuating member is a bell crank lever 34 connected to the locking member 35. By referring to Fig. 7, it will 30 be seen that a push inward upon the actuating member 33 will cause the bell crank lever 34 to assume a position which will retract the locking member 35 from engagement with a recess 36 formed in the section 30, allowing said section to swing into position 35 to be drawn into the interior of the cabinet body. As shown in Fig. 5, one edge of the cabinet body is cut away at 37, forming an overhanging ledge 38, which acts as a stop against which the door rests when it is 40 swung into position to form a closure for the cabinet.

In Fig. 8 is shown a modified construction, which consists of a rack formed with a plurality of holes 39 in place of the gear teeth 16; and in place of the pinions 17 and 18 is shown a toothed wheel 40, the formation of the teeth 41 being such as to adapt them to enter the holes 39 in the trackway.

The operation is as follows: When the 60 operator releases the mechanism shown in Fig. 7, the spring hinges 31 will act to swing the section 30 into the position shown in Figs. 1 and 2. When the section has reached such position it will then be clear of the 65 stop member, and the tension produced by

the weight 29 will cause the sliding and swinging sections to be pulled into the interior of the cabinet body, the sections being guided in their movements in and out of the cabinet body by the pinions 17 and 18 70 and by the rollers 25 and 26. All of these movements necessary to the positioning of the door within the cabinet body are accomplished automatically, the only action on the part of the operator being the moving of 75 the actuating member 33 to release the locking mechanism. The stop member 32 forms means whereby the door cannot be drawn into the interior of the cabinet until it has swung into the position shown in Figs. 1 80 and 2, that is, parallel with the side walls of the cabinet, thus preventing any danger of the door being drawn inward while it is yet swung at an angle and coming in contact with a shelf or other obstacle located in 85 the interior of the cabinet body and being damaged. Also the pinions 21 form locking means which prevent the upper edge of the door traveling into the interior of the cabinet faster than the lower edge, or vice versa, 90 which course of travel would cause a binding between the door and the trackway upon which it slides, thus making the door difficult of operation.

I claim:

1. In a device of the class described, the combination of a cabinet body, a door for said body, comprising a sliding section and a swinging section hinged together, rack bars secured to one of the side walls of said cabinet body at points adjacent to the top and bottom thereof, trackways located adjacent to said rack bars, pinions carried by said sliding section traveling upon said rack bars, a rod extending longitudinally of the 105 sliding section upon which said pinions are mounted, rollers carried by said sliding section traveling upon said trackways, the roller and trackway coöperating with one another to form a mounting for the slideable 110 section, and to prevent the movement of the pinions away from the rack bars, means for exerting a tension upon the sliding section, tending to draw it into the interior of the cabinet body, means for preventing such inward movement of the sliding section until the swinging section has been swung into parallel alinement with the sliding section, means for preventing any swinging movement of the swinging section until the sliding section has reached its limit of movement toward the front of the cabinet body, and means for locking the swinging section when it is swung into position to form a closure for the cabinet, substantially as described. 115

2. In a device of the class described, the combination of a cabinet body, a door for said body, comprising a sliding section and a swinging section hinged together, companion plates of angle-iron formation se- 120 125 130

cured to one of the side walls of the cabinet body at points adjacent to the upper and lower edges thereof, each of the plates having gear teeth formed on one of its projecting portions, the other projecting portion forming a trackway, pinions carried by the sliding section traveling upon said gear teeth, rollers carried by said sliding section traveling upon said trackways, means for maintaining a tension upon said sliding section, tending to draw it into the cabinet body, and means for locking the swinging section when it has been swung into position to form a closure for the cabinet, substantially as described.

3. In a device of the class described, the combination of a cabinet body, a door for said body, comprising a sliding section and a swinging section hinged together, companion plates of angle-iron formation secured to one of the side walls of the cabinet body at points adjacent to the upper and lower edges thereof, each of the plates having gear teeth formed on one of its projecting portions, the other projecting portion forming a trackway, companion plates of angle-iron formation carried by the sliding section, a rod journaled in one of the projecting portions of each of said plates, pinions mounted upon said rod and traveling upon the above mentioned gear teeth, rollers journaled in the other projecting portion of said plates carried by the sliding section and traveling upon the above mentioned trackways, means for maintaining a tension

upon said sliding section, tending to draw it into the cabinet body, and means for locking the swinging section when it has been swung into position to form a closure for the cabinet, substantially as described.

4. In a cabinet, a trackway for a slidable door, consisting of a single piece of metal having a flat upper edge and a longitudinally extending toothed surface, a roller carried by the door, and a rotatable toothed member carried by the door, the roller traveling upon the upper surface of the plate and serving to insure the easy travel of the door into and out of the cabinet, the toothed surface of the plate and the rotatable toothed member coöperating to insure the even travel of the door into and out of the cabinet, substantially as described.

5. In a cabinet, a trackway for the slidable door, consisting of a single piece of metal of angle iron formation, having one edge serrated and the other edge smooth, a plate of angle iron formation, carried by the slidable door, and a member journaled in one of the projecting portions of said plate, and having a serrated surface adapted to mesh with the serrated surface of the trackway, the other projecting portion having a member journaled therein, and adapted to travel upon the smooth edge of the trackway, substantially as described.
